UNITED STATES PATENT OFFICE.

CLIFTON CHISHOLM, OF CLEVELAND, OHIO, ASSIGNOR TO THE AMERICAN MULTIGRAPH COMPANY, OF CLEVELAND, OHIO, A CORPORATION OF OHIO.

ADDRESSING MACHINE.

Application filed November 26, 1920. Serial No. 426,412.

To all whom it may concern:

Be it known that I, CLIFTON CHISHOLM, a citizen of the United States, residing at Cleveland, in the county of Cuyahoga and State of Ohio, have invented a certain new and useful Improvement in Addressing Machines, of which the following is a full, clear, and exact description, reference being had to the accompanying drawings.

10 The object of this invention is to provide an efficient mechanism for printing addresses from separate address plates fed one after the other from a stack in a magazine and presented simultaneously with paper between impression members, the paper and the plates being non-interferingly delivered following the impression.

20 One of the important characteristics of the invention is the feeding of the plates and the paper together thru the impression couple and immediately thereafter the transporting of the plate laterally while the paper is delivered as a substantial continuation as its forward feed. This feature enables the plates to be effectively restacked in a vertical drawer, which is readily accessible at the side of the machine. At the same time the envelope, or other printed matter, is delivered in the front of the machine in the most convenient position.

30 The above and other features of the invention will be apparent from the following detailed description of a preferred embodiment shown in the drawings, the essential 35 novel features of the invention being set out in the claims.

In the drawings, Fig. 1 is a side elevation of my addressing machine; Fig. 2 is a vertical section thereof in a plane parallel with 40 Fig. 1; Fig. 3 is a front elevation; Fig. 4 is a plan.

45 Various characteristics of the complete machine shown are claimed in applications of mine heretofore filed as hereinafter referred to, but for the sake of completeness the entire machine shown will be described.

The general frame of the machine consists of a horizontal bed 10, shown as resting on a suitable stand 11, and two upright end frame plates 12 and 13, secured to the bed. The bed carries at its rear a vertical supply magazine for a stack of address plates. This magazine is of a skeleton form,

and, as shown, comprises two angle bars 20 and two channel bars 21 standing at the 55 four corners of a rectangle and braced by cross members, some of which are indicated at 22. This magazine is adapted to carry a vertical stack of superimposed address plates. Each plate is preferably mounted 60 in a suitable holder and the holders are normally stored in a drawer. This drawer may be inserted vertically from above in the magazine and then the plate released and the drawer withdrawn, leaving the stack of 65 plates in the magazine.

Extending thru the lower portion of the magazine are two conveyer chains 25, mounted at their rear ends on sprockets 26 and at their forward end by sprocket wheels 70 27. Each conveyer chain has operable extending lugs 28, spaced equal distance on the chain a distance apart corresponding to half the periphery of one of the sprocket wheels 27, which distance is somewhat 75 greater than the width of a plate or holder. Chains are driven with their upper reach traveling forward, that is to the left in Figs. 1 and 2, and operate to carry in that direction successively the bottommost plate in 80 the stack.

The sprocket wheels 27 are tight on a shaft 30, by which the chains are driven. The sprocket wheels 26 are mounted on a shaft which is journaled in a bracket 32, 85 pivotally mounted at 33 on the frame and adjusted in position by set screws 34 and 35.

Between the sprocket wheels 27 and loosely mounted on the shaft 30 is an impression platen 40. This platen has the same diameter as the sprocket wheels 27. Directly above the shaft 30 is a shaft 42 on which is mounted a paper feeding drum 45 of twice the diameter of the platen 40. This drum has two diametrically opposed platen members 46, while between these segmental platen members are arcuate strips 47. The segmental plates of the arcuate strips constitute in effect a continuous drum. 48 and 49 indicate pressure rolls adapted to bear 100 against the paper and hold it on the drum as it is being fed from above. These rolls extend thru openings in a curved shield 50 substantially concentric with the drum.

If the machine is to print envelops these 105 are stacked in an inclined magazine, shown

as consisting of two angle members 52 and a front plate 53. The envelopes are suitably fed from the bottom of this stack by means hereinafter described, toward the right in 5 Fig. 2 and downwardly concentric of the drum between the drum and shield 50, and then pass downwardly with the address plates between one of the segmental platens and the platen roller 40, whereby they are 10 printed, the plate having been inked intermediately of its passage from the supply magazine to the impression members.

To ink the plate I may provide a storage ink roller 60, mounted in engagement 15 with a delivery roller 61, which contacts with the plate in its passage, the plate being supported on its under side by supporting rolls 62.

The means shown for feeding the envelopes 20 consists of a pair of arms 65, pivotally mounted on sleeves 66 slidable on but rotatable with the shaft 42. Each of these arms has a finger 67 at each end adapted to engage beneath the flap of the lowermost envelop in the stack. As the arms 25 are rotated they are swung on their axes by stationary cams 68, which cause their upper ends to swing inwardly bringing the fingers above the flap of the lower most envelop. These fingers, then in the continued 30 rotation of the arms, drag this envelop from the bottom of the stack so that it is fed around the drum between it and the shield 50 and thus brought to the printing position. Just before it comes into this position the swinging of the arms cause the fingers to clear the envelop. The arrangement of 35 the two segmental plates 46 and the fingers on each end of the arms provide for the feeding of two envelopes for each rotation of the drum. This is the normal operation, though the machine may be adjusted to feed only one envelop or sheet for each rotation, which is hereinafter explained.

40 It will be understood that the mechanism, so far described, will deliver an inked plate and an envelop to the impression point for each half rotation of the sprocket wheels 27 and each half rotation of the paper drum which, under these circumstances, has the same angular speed as the sprocket 45 wheels. Following the impression the paper continues a substantial horizontal travel and passes between upward delivery rolls 50 and a coacting lower roller 71. In the 55 case of envelopes these parts are so positioned that they tip the envelop diagonally downward. The envelop is thus fed down the inclined chute 73 and passes into the groove of a stacker cam 74. This cam is 60 continuously rotated in the direction of the arrow and thus lowers the envelopes into vertical position and thereafter the shoulder 75, on the cam, impinges the envelop and 65 forces it toward the left, and the envelopes

are thus stacked in a horizontal row on the tray 78 against an abutment 79.

At the same time that the paper is passing substantially horizontally from the impression point to the delivery rolls the plate, 70 freed from the impression members, drops downwardly onto the upper reach of a laterally traveling belt 80 behind an inclined shield 81. This inclined shield carries stationary fingers 83 projecting toward the impression 75 point and insuring the separation of the plates from the paper. These fingers are preferably sheet metal members bifurcated at their ends to provide two tongues, one lying over the inclined ledge 81 and the other beneath such ledge. The belt 80 carries the plate toward the side, that is toward the right of the operator as he faces the front of the machine, the front of the machine being positioned 85 where the envelopes are stacked. This delivery of the plates is mainly horizontal but somewhat downwardly and terminates in the restacking mechanism, which I will now describe.

The restacking magazine includes an upright housing 90 adapted to contain a vertical drawer to receive the plates, the plate being fed into the upper end of the drawer upon a suitable supporting platform or elevator 91, within the drawer, which is gradually lowered to support the accumulated stack of plates. In the ordinary operation 95 of the machine, after the drawer has deposited its stack of plates in the supply magazine, this empty drawer is placed in the restacking housing 90 in position to receive the plates following their printing operation.

The elevator platform 91 is slidably 105 guided within the housing 90 and supported by a sprocket chain 92, which passes over a sprocket wheel 93 and carries at its end a counterweight 94 adapted to elevate the platform. When it is unloaded the sprocket 110 wheel 93 is tight on a shaft 96 to which a clutch sleeve 97 is splined. Loose on this shaft is a driving worm wheel 98, having a pin with which the clutch sleeve may engage. A shipper lever 99 serves to shift the 115 sleeve 97. When the clutch is in engagement the elevator platform 91 is supported by the sprocket mechanism and is gradually lowered as the worm wheel 98 is revolved. When the clutch members are separated the 120 counterweight 94 returns the platform to its upper position. This separation takes place automatically when the filled drawer is withdrawn from the housing 90. This filled drawer engages a cam shoulder 101 on a 125 shipper lever 99, so that when the drawer is inserted the clutch is engaged, while when the drawer is withdrawn a spring 102 acting on the lever disengages the clutch.

It will be understood from the description 130

given that immediately following the printing, the plates drop and are carried to the side and are restacked in a vertically positioned drawer, while the printed envelope 5 continues its travel forwardly. By this means I am enabled to use a vertical restacking magazine at the side of the machine, which I have found to be much more convenient than a horizontal position for the receiving drawer, as employed in some other machines. It also enables the rest of the machine to be built in a very compact form. This travel of the plate—downwardly, forwardly, laterally, downwardly—and the 10 means for accomplishing it are features of the present invention.

The drive for the various traveling members shown is as follows: Power is received on a pulley 110. A clutch 111 delivers power 20 to the shaft 42. This shaft is geared as hereinafter described with the shaft 30. A sprocket chain 113 runs from a sprocket wheel on the shaft 30 to a sprocket wheel on the shaft 115 carrying the stacker cams 74. 25 This shaft 115 has a pinion 116 meshing with a pinion on a shaft 117, which carries a worm meshing with the worm wheel 98. A belt running from the drive shaft 42 leads to a pulley 120 on a shaft 121, which 30 is connected by beveled gears with the shaft carrying one of the pulleys 123, over which the delivery belt 80 runs.

It will be seen that the movement of all the parts is controlled by the main clutch 35 111. This clutch may be operated manually by the handle 125 of a shipper lever 126, or it may be controlled automatically upon the failure of paper or plates, as now about to be described.

40 In the periphery of the paper feeding drum are formed arcuate grooves 130, there being two of these grooves near one edge of the drum and one groove near the other. Co-operating with the drum in the plane of the two grooves is an arm 132, carrying a roller adapted to ride on the paper over the grooves. A similar arm 133 carries a roller in the plane of the single groove. These rollers are loosely mounted on a frame rod 45 135. Each of them carries a pin adapted to stand in the path of a crown cam 143 on a longitudinally shiftable rotatable shaft 144. This shaft is connected at its end with a plate 146 extending from the shipper lever 50 126.

When the machine is operating normally to print two envelopes for each rotation of the paper feeding drum, the arm 133 co-operating with a single groove in the drum 55 is held in idle position (by means hereinafter described), but the other arm 132 has its roller in position to ride on the envelopes. These envelopes when present, bridge the grooves 130. If, however, an envelope is absent due to the envelope magazine becoming

empty or some failure to feed the roller, the roller drops into the groove and the pin on the arm engages the crown cam 142 and causes the shaft 144 to shift lengthwise, thus moving the shipper lever 126 to open the 70 clutch.

I have referred to a machine being adapted to print envelopes or paper only once for each rotation of the drum, instead of twice as normally. This is to provide for extra large 75 envelopes or for sheets of paper. In this case the paper feeding drum instead of making one rotation for each rotation of the sprocket wheels 27 will make two rotations for each rotation of those wheels. Thus 80 there will be fed one envelope for one rotation of the drum to be printed by the address plate fed by a half rotation of the sprocket wheels. The normal operation is provided for by a gear 150 rigid on the 85 shaft 30, and an equal sized gear 151, which is then clutched to the shaft 42. The special operation is provided for by a large gear 153 rigid on the shaft 30, meshing with the gear 154 of half its diameter, which may be 90 clutched to the shaft 42. When equal sized gears are acting, of course the drum makes a rotation for each rotation of the sprocket wheels. When the other gears are acting the 95 drum will make a rotation for each half rotation of the sprocket wheels.

The clutching of one or the other gear 151 or 154 to the shaft 42 is checked by a sliding key 160 shifted by a bracket 161. When this bracket is shoved inwardly to clutch the 100 gear 151 a cam 165 on a longitudinally movable rod 166 connected with the bracket engages the arm 133 and raises it to idle position. When the bracket 151 is pulled outwardly to clutch the gear 154, the cam 165 105 releases the arm 133, while a cam 167 raises the arm 132 to idle position. Accordingly, one or the other arm 132 or 133, is active according to whether the mechanism is set for feeding two envelopes or one envelope for 110 each rotation of the envelope feeding drum. The rotation of the shaft 144 by which its cams may cause its longitudinal shifting, may be effected in any desired manner. As shown power is delivered to a broad pinion 115 170 on the shaft by an idler gear 171 rigid with a pinion 172, which meshes with the gear 151.

To effect a stoppage of the machine in case the supply magazine becomes empty, I provide an arm 180 and a spring 181 tending to swing the lower end of this arm into the magazine. The arm engages the plates in the magazine so that when any plates are presented, the arm cannot have this swinging operation. If plates are absent, however, the spring will pull the upper end of the arm toward the left in Fig. 1, which will move a link 183 to swing an arm 185 downwardly to cause a pin thereon to stand in the 130

path of a crown cam 187 on the rod 144. The effect, therefore, is to shift the clutch and stop the operation whenever the plates fail. A main clutch may be shifted manually whenever desired by the operation of the hand lever 125. It may also be periodically released and restored by a pivoted bar 190 drawn upwardly by a spring 191 into position to separate the clutch members. A trigger mechanism 193, which may be operated by a treadle not shown, serves to draw the bar downwardly to release the clutch, the bar immediately springing back to a position shown in Fig. 1 to engage the clutch and stop its operation at the end of a complete rotation. This enables the machine to be controlled in periodic cycles with a rest between them, which is suitable for hand feeding of the paper.

As heretofore stated, the address plates are intended to be deposited in the supply magazine by the insertion of a drawer therein, carrying the plates, and the subsequent withdrawal of the plate. 200 in Fig. 1 indicates a cam adapted to operate release mechanism on the drawer to release the plates therein when the drawer is put in place in the magazine. In this same view, I have shown at 202 a sliding rod normally drawn upward by a spring 203 and carrying shoulder 204 adapted to be engaged by the drawer when inserted. The drawer will thus shove this lever downwardly. Upon such movement a pallet 206 connected with the rod engages a pallet lever 207 on the shaft carrying the sprocket wheels 26 and turns them forwardly as much as may be necessary to properly position the lugs on the chain with reference to the address plate. When the drawer becomes empty, the momentum of the machine may carry the pins forwardly beyond the desired position for properly engaging the plates; but the mechanism just described automatically corrects this immediately upon the insertion of the subsequent drawer of plates.

Reference may be made to the following patents and applications of mine for a fuller description of various mechanisms above described as well as for claims thereon, as follows:—

Patent No. 1,285,623, November 26, 1918, for the envelop feeding mechanism.

Application No. 371,372, filed April 6, 1920, for the variable gearing for synchronizing the plates and envelopes.

Application No. 417,579, October 18, 1920, for a suitable inking device.

Application No. 417,580, October 18, 1920, for mechanism for positioning the conveyer.

Application No. 418,761, October 22, 1920, for the main clutch.

Application No. 418,762, October 22, 1920, for the restacking mechanism.

Applications No. 419,222, October 25, 1920,

and No. 425,476, filed November 20, 1920, for the automatic stop mechanism and the connection with its change speed gearing.

Application No. 420,415, October 29, 1920, for the paper feeding platen.

Application No. 424,114, November 15, 1920, for the delivery mechanism.

Reference may also be made to my application No. 410,710, September 16, 1920, for a suitable address plate holder for use with the machine, and to my application No. 416,359, October 12, 1920, for a drawer for holding the address plates.

Having thus described my invention, I claim:—

1. In an address printing machine, the combination of an upright supply magazine, means for transporting plates forwardly from the bottom of the magazine, a pair of impression rollers to which the plates are fed, means for transporting the plates laterally following their impression, and an upright receptacle in which the plates are then stacked one above the other.

2. In an address printing machine, the combination of an upright supply magazine, a conveyer adapted to feed plates from the bottom of the magazine, a pair of impression rolls between which the plates travel, and a conveyer in front of said rolls adapted to travel laterally.

3. In an addressing machine, the combination of a supply magazine, a conveyer for feeding plates forwardly therefrom, impression mechanism between which the plates pass, a lateral conveyer in front of the impression mechanism, and a downwardly extending restacking mechanism to which the lateral conveyer delivers the plates.

4. The combination of an upright supply magazine, a conveyer for feeding the bottom plates therefrom forwardly, a pair of impression rolls between which the plates travel, a lateral conveyer in front of the impression rolls, a restacker platform onto which the plates are delivered by the lateral conveyer, and means for lowering said platform to allow the plates to stack in a superimposed pile.

5. The combination of an upright supply magazine into which a drawer may be placed, a conveyer adapted to feed plates forwardly from the bottom of the magazine, impression members between which such plates travel, a lateral conveyer receiving the plates in front of the impression member, and a restacking mechanism adapted to hold a drawer upright and in position to receive the plates adjacent to its upper end.

6. The combination with an upright supply magazine adapted to carry a superimposed stack of plates, a belt conveyer for transporting the plates from the bottom of the stack, a platen adapted to cooperate with the plates to print, a lateral belt conveyer

for transporting the plates after printing, and means for holding a drawer in an upright position, and stacking therein in a vertical pile the plates as delivered by the lateral conveyer.

7. The combination of a supply magazine, and a conveyer for feeding plates therefrom, an impression member adapted to coact with the fed plate, a lateral conveyer beyond the impression member, and a separator adapted to insure the separation of the paper and plate after printing.

8. The combination of a supply magazine for address plates, a supply magazine for paper to be printed, a pair of impression rolls, means for feeding the plates and paper simultaneously through the impression rolls, means for transporting the plate laterally following the impression, and means for delivering the printed paper substantially forwardly following the impression.

9. The combination of a supply magazine for plates, a holder for envelops to be printed, a pair of impression rolls, a conveyer for feeding plates to the rolls, and means for presenting envelops to the rolls at the same time, a delivering mechanism for receiving the printed envelop and transporting it forwardly, and a laterally moving conveyer for moving the plate toward the side.

10. The combination of an upright supply magazine, a conveyer for feeding plates forwardly from the bottom thereof, a magazine for a stack of envelops, means for feeding envelops from the bottom of the stack downwardly into coaction with the plates, a pair of impression rolls through which the plates and envelops pass simultaneously, a lateral conveyer for the plates in front of the impression rolls, and means for delivering and stacking the envelops in front of the lateral conveyer.

11. The combination with a supply magazine and means for feeding plates therefrom, means for feeding paper to be printed by the plates, impression mechanism simultaneously acting on the plates and paper, a lateral conveyer to transport the plates after printing, and a separator acting between the plates and paper after printing.

12. The combination with a supply magazine and means for feeding plates therefrom, means for feeding paper to be printed by the plates, impression mechanism simultaneously acting on the plates and paper, a lateral conveyer to transport the plates after

printing, and a shield overhanging the conveyer, and having separating fingers adapted to extend between the plates and paper. 60

13. The combination of a supply magazine, means for conveying plates therefrom, a paper feeding mechanism, a pair of impression rollers between which the plates and paper are simultaneously fed, a lateral 65 conveyer for the plates in front of the rollers, a delivery mechanism for the paper above and in front of the lateral conveyer, and a separator extending above the conveyer and adapted to stand above the plates 70 and below the paper.

14. The combination of a conveyer for feeding plates, means for feeding paper, a pair of impression members between which the paper and plates may pass simultaneously, a laterally extending trough in front 75 of said impression members, a conveyer belt in said trough adapted to transport the printed plate laterally.

15. The combination of a conveyer for 80 feeding plates, means for feeding paper, a pair of impression members between which the paper and plates may pass simultaneously, a laterally extending trough in front of said impression members, a conveyer belt 85 in said trough adapted to transport the printed plate laterally, the forward edge of said trough extending over the conveyer belt and separator fingers carried by the said forward edge and extending toward the impression members. 90

16. The combination of means for conveying address plates, means for feeding paper, impression members between which the plates and paper travel simultaneously, a 95 lateral conveyer in front of the impression members, means for delivering the printed paper in front of the conveyer, and means for restacking the plates in a vertical pile and delivered at the side of the machine. 100

17. In an addressing machine, the combination with means for holding a stack of envelops, and means for holding a stack of address plates, and means for feeding envelops from the bottom of their stack 105 downwardly and forwardly, and means for feeding plates from the bottom of their stack forwardly, then laterally, then downwardly, and impression members between which both the envelops and plates pass on 110 their forward travel.

In testimony whereof, I hereunto affix my signature.

CLIFTON CHISHOLM.
